ABSTRACT: A dispenser for a nested stack of receptacles, such as drinking cups, comprises a pair of adjustable coacting clamp members for holding a carton of the nested stack at diagonally opposite corners of the carton. Means are provided for mounting the clamp members on a wall bracket. The clamp members each comprise angular sections of a vertical plate and tapered embossments on inner surfaces of the sections to act as detents for removing the receptacles one by one. Horizontal abutments are also carried by the plates above their lower edges for engaging the bottom of the carton, whereby the stack drops below the carton onto the detents and the lower portion of the stack becomes visible to indicate when refilling is necessary.

PATENTED AUG 31 1971

FIG. 1.

FIG. 2.

FIG. 3.

FIG. 5.

The diagram shows a vertical stack of four distinct layers. Layer 42 is the top-most, thin, light-colored layer. Layer 45 is the bottom-most, thick, light-colored layer. Layer 46 is a thin, dark-colored layer positioned between the top and bottom layers. Layer 47 is a thick, dark-colored layer at the very bottom of the stack. The stack is shown from a side-on perspective, with the top and bottom edges slightly curved.

**CLAMP MEANS FOR HOLDING RECEPTACLE
DISPENSER CARTONS**

This invention relates to dispensers and it is more particularly concerned with receptacle dispensers, such as drinking cups, for example.

An object of the invention is the provision of receptacle dispensers which are adjustable to different sizes of receptacles.

Another object is the provision of a receptacle dispenser in combination with means for mounting it in a position to be used.

A further object is the provision of a receptacle dispenser which is adapted to support in a vertical position nested receptacles to be dispensed and a carton containing such receptacles.

A feature of the invention is the provision of means for supporting the nested receptacles in a carton in which they are contained which permits visual observation of these receptacles as the carton becomes nearly exhausted and requires immediate replacement.

These and still further objects, advantages and features of the invention will appear more fully from the following description considered together with the accompanying drawing which illustrates an embodiment of the invention.

In the drawing:

FIG. 1 is a perspective view of the embodiment with a sleeve carton of receptacles in place.

FIG. 2 is an enlarged perspective view of the embodiment apart from the carton of receptacles on a larger scale.

FIG. 3 is a cross-sectional view along the line 3—3 of FIG. 1.

FIG. 4 is a sectional view along the line 4—4 of FIG. 3.

FIG. 5 is a sectional view along the line 5—5 of FIG. 3.

Referring with more particularity to the drawing in which like numerals designate like parts, the embodiment illustrated comprises a pair of oppositely facing vertical clamp members 11 and 12, having angularly disposed sides 13, 14 and 15, 16, respectively. The rear sides 13 and 15 have rearwardly extending portions 17 and 18, respectively, and inwardly turned flanges 19 and 20, respectively.

The flanges 19 and 20 overlap one of the flanges, say, flange 20 is provided with horizontal slots 21 which register with apertures 22 in the other flange 19 and apertures 23 in a mounting plate 24. Bolts 25 are disposed in the slots and also through the apertures 22 and 23. Nuts 26 on the bolts permit easily mounting and adjusting the spacing of the clamp members 11 and 12 relative to each other.

The mounting plate 24 has opposite rearwardly divergent sidewalls 27 and 28 which are slidably engageable with a wall bracket 29 having slots 30 and 31 on either side to engage the sidewalls 27 and 28. The slots 30 and 31 are formed between a backplate 32 and forwardly extending spaced panels 33 and 34. The panels 33 and 34 have abutment flanges (not shown) at the bottom for contacting the sidewalls 27 and 28 of the mounting plate 24 and limit its placement with respect thereto.

Apertures 35 in the backplate 32 are for securing it to a wall 36 by nails or screws 37.

The upper edges of sides 13, 14 and 15, 16, respectively, have outwardly flared marginal portions 38, 39 and 40, 41 to facilitate the placement of a sleeve carton 42 between the clamp members.

At the inside corners between the sides 13, 14 and 15, 16, there are disposed horizontal shelves 43 and 44, respectively, to support the lower edge of the sleeve carton 42 exclusively of the receptacles therein.

Each of the sides 13, 14, 15 and 16 is provided with median tapered embossments 45 adjacent the bottom edge. These embossments slope inwardly and upwardly thereby providing detents for beaded edges 46 of receptacle cups 47, for example, which drop below the open bottom of the sleeve carton 42. The device may also be used by removing entirely the carton sleeve 42 and leaving the entire stack of cups 47 exposed.

I claim:

1. A holder for dispenser cartons containing a stack of nested receptacles to select dispensing position comprising a pair of coacting clamp members, said members embracing a major portion of the four sides of an upright carton at the lower end thereof, means for holding said members in adjusted, coacting positions relative to each other, means for mounting the members in a vertical position on a surface, and horizontal shelves carried by the members at diagonally opposite corners for engaging the lowermost diagonal corners of the dispenser carton independently of the nested receptacles of the stack.

2. A holder for dispenser cartons containing a stack of nested receptacles to select dispensing position as defined by claim 1 in which the clamp members comprise each a vertical plate bent to form angularly disposed vertical sections to engage four sides of said upright carton and to engage only diagonal corners of the dispenser carton at the apex of connected sides of the carton.

3. A holder for dispenser cartons containing a stack of nested receptacles to select dispensing position as defined by claim 2 in which the angularly disposed sections of the vertical plate have outwardly flared upper marginal edges to guide dispenser cartons into dispensing position.

4. A dispenser for a stack of nested cups in a carton of square cross section comprising a pair of clamp members having four surfaces to engage the carton sides defining diagonally opposite corners and a lower major portion of four sides of the carton, said members comprising a pair of plates, each of the plates being formed to provide an internal apex, means for holding said members in adjusted coacting positions relative to each other, means for mounting the members in a vertical position with the respective apex of each facing each other, horizontal abutments carried at the interior apex of each pair of plates for engaging the edges of the bottom open end of each opposite diagonal corner of the carton to the exclusion of the cups in the carton, and detents carried by the interior side of each of the members for frictionally engaging the lowermost cups of the stack.
